AUTOCLAVABLE PROSTHESIS CONTAINER

David L. Walchle and James L. Geraci, Cincinnati, Ohio,
assignors to Xomox Corporation, Cincinnati, Ohio

Filed May 8, 1972, Ser. No. 251,559

Term of patent 14 years

Int. Cl. D24—99
U.S. Cl. D83—1 W

FIG-1

FIG-2

FIG-3

FIG-4

FIG-5

FIG-6

FIG-7

FIG. 1 is a top perspective view of one side of the autoclavable prosthesis container showing our new design.

FIG. 2 is a top plan view of FIG. 1.

FIG. 3 is a bottom plan view of FIG. 1.

FIG. 4 is an elevational view as seen from the right side of FIG. 1.

FIG. 5 is an elevational view as seen from the front of FIG. 1.

FIG. 6 is an elevational view as seen from the rear of FIG. 1.

FIG. 7 is a view of FIG. 1 showing the container in an opened position.

We claim:

The ornamental design for an autoclavable prosthesis container, as shown and described.
